UNITED STATES PATENT OFFICE.

JOHN B. WHITNEY, OF NEW YORK, N. Y.

DESIGN FOR HINGES.

Specification forming part of Design No. **6,362**, dated January 21, 1873.

A.

To all whom it may concern:

Be it known that I, JOHN B. WHITNEY, of the city, county, and State of New York, have invented a new and original Design for a Hinge, of which the following is a specification:

The accompanying engraving fully represents my new design.

This invention relates to a new ornamentation of metallic hinge-plates, and consists in forming bas-relief circular center ornaments

thereon, and foliated scrolls toward the end. Each circular centerpiece has a beaded border, and contains a cross with leaves between the arms of the same.

I claim as my invention—

The design for a hinge-plate, as shown.
JOHN B. WHITNEY.
